METHOD OF MAKING A RUBBERLIKE
CLEANING COMPOSITION

Hans Blumberg, Peabody, Mass.

No Drawing. Application October 19, 1945,
Serial No. 623,435

4 Claims. (Cl. 252—165)

1

This invention relates to hand cleaner compositions which are of a type characterized by the fact that they may be employed for the complete cleaning of the hands, without the use of either water or towels of any kind.

It is found, in accordance with the discovery of this invention, that certain substances may be converted chemically to a form having a consistency which constitutes a soft solid base which may be dispersed in finely divided form into stiff emulsions or paste-like plastic creams. And it is further found that these substances, in such dispersed condition, upon being subjected to rubbing friction, break the dispersion and coalesce into aggregates, having moist soft surfaces which are highly adsorbent and of an increasing frictional resistance as the exposed moist surfaces gradually become dry.

For the preparation of the solid base constituent of these properties it is found that fatty oils generally may be employed including vegetable oils, such as corn oil, linseed oil, mustard seed oil, soya bean oil, castor oil, cottonseed oil, and peanut oil (but not coconut oil) fish oil (but not sperm oil) and lard oil, as well as a number of the waxes.

In general I have found that the fatty oils—as exemplified by those mentioned above—may be uniformly and completely converted to the soft solid form, and that when this is done, the resulting product is characterized by the properties above described, which make it applicable to be used as the base or principal ingredient of a dry hand cleaner composition.

One procedure for converting the fatty oil to the desired semi-solid form is to subject it to sulphur chloride (monochloride), the reaction being controlled by a preliminary neutralization of the oil with an excess of an alkali, such as lime, hydrated lime, etc.

A further control of the conversion of the fatty oil, may be effected by diluting the reactants, e. g. by diluting the sulphur mono-chloride with high boiling inert petroleum solvents, such as Stoddard solvent, which has an initial flash point of 117° F., an initial boiling point of 311° F. and final boiling point of 411° F.

The reaction may also be retarded against a too rapid or uneven development throughout the charge or too drastic a degree of conversion of the fatty oil, or to a too solid consistency, by incorporating a voluminous material into the charge which is inert to the reaction, such as potato starch, in proportions up to approximately 10%, for example, on the weight of the oil.

2

A still further control of the rate and degree of the conversion of the fatty oil for the purposes of this invention is effected by cooling the reagent materials preliminary to their addition and admixture and/or by making such admixtures gradually, with intimate agitation and suitable provisions for cooling the reaction mixture.

And finally, the solidified products, obtained by the controlled but complete reaction of the fatty oils with the sulphur chloride may be effectively stabilized in the condition developed by the foregoing procedures by the addition of neutralizing agents such as lime, magnesium carbonate, urea, terpenes, and soaps, and more especially soaps of polyvalent metals such as the aluminum soaps of coconut oil, Japan wax, and the like.

By such procedure and controls, the fatty oils are reacted and developed to a semi-solid condition, from which they may be reduced to finely divided or colloidal condition and dispersed in suitable media to develop resulting compositions of various consistencies and properties. Ordinarily liquid vehicles will be used for this purpose forming emulsions, or soft or stiff pastes, according to the proportions, but often solids may be added and gases may act as a dispersing medium, in the form of bubbles or the like, within the invention.

A representative example of the practical carrying out of the invention, which results in a composition of preferred properties as a dry hand cleaner, is as follows:

Mix 100 parts by weight of refined soya bean oil with 6-12 parts by weight of hydrated lime, and then cool the reaction mixture at least to 50° F., or preferably to lower temperatures.

Sulphur mono-chloride (15 parts by weight) is then diluted with one-third of its volume of Stoddard's solvent (or other inert high-boiling petroleum solvent of suitable consistency).

The diluted sulphur mono-chloride is then added slowly to the alkaline reaction product of the soya bean oil and lime, with continued stirring of the mixture. This mixture is then again allowed to cool to 50° F., or below.

As a further advantageous, supplementary control of the reaction and of the consistency of the reaction mass, potato starch may be added in the preparation, as above mentioned, at this point.

A second quantity of sulphur mono-chloride (19½ parts by weight) is then diluted with one-half its volume of Stoddard solvent, or similar inert high-boiling petroleum solvent. This is

then also added slowly to the cooled reaction mixture, while vigorously stirring.

In about 15 or 20 minutes thereafter the whole reaction mass solidifies into a firm rubber-like substance of light color. After aging several days (at room temperature) the mass is broken up and ground. Prolonged aging will greatly improve the product thus obtained and promote its disintegration to finely divided form, as a crumbly mass.

Since the product as thus obtained contains considerable free lime which may have a harsh action upon the hands, it is well to remove it. This may be done by washing with water or by neutralizing. Lactic acid serves this purpose with good success. It is, however, desirable to leave and maintain a slight excess of alkali as it will act as a stabilizer.

The end product is a light crumbly solid which constitutes the basic ingredient of the hand cleaner composition.

A typical dry hand cleaner composition may accordingly be prepared as follows:

100 parts of the product, obtained as above described and reduced at least to granular form.
 30 parts diethylene glycol mono-ethyl ether
 20 parts di-glycol laurate
 10 parts sorbitan mono laurate.
 50-60 parts water (with or without the addition of methyl cellulose)
 Fillers, abrasives and perfumes, as and if desired.

The finely divided base may be first mixed well with the sorbitan mono laurate, the water being then added and thoroughly mixed, followed by the remaining ingredients. The composition as thus obtained is advantageously milled in a paint mill to a smooth, uniform cream or paste. In this condition, the composition is ready for packaging, storage or immediate use.

The consistency of the product may be varied somewhat, according to the intended use, as already indicated. Thus abrasives may be added for especially active cleaning action. Other fillers may be added, with a milder action of the same sort. In addition, the consistency may be varied from a stiff, hard paste, useful in cases where this may seem the more effective, to a soft, wet paste, cream or even an emulsion stage, if desired.

In general, the action of the composition, upon rubbing on and between the hands, is first to spread it out, and then to break the emulsion and coagulate it into separate crumbs, which are coarse, slightly adherent, but soft solid particles. These are adsorbent, plastic, soft, and moist and characteristically roll up in the hand, carrying with them the dirt, grease and all foreign matter from the surfaces, pores and wrinkles of the skin. The liquid components are absorbed by the skin, or evaporate into the air. Consequently, the composition passes from a soft, creamy or even fluid condition to an increasingly firm, solid condition with continued rubbing, and finally forms into dry, pasty solid particles which soon dust off from the hands completely, leaving them suitably dry and thoroughly clean but soft and without any harsh action chemically or physically such as by chapping or scratching.

The action of the cleaner composition, as above described, may be varied in several ways by the compounding ingredients employed. Thus an increased proportion of water or other liquid will render the mixture softer or more fluid and hence

of somewhat slower action on the hands while it is drying off or being absorbed by the hands. It is found, on the other hand, for example, that by adding polyvinyl acetate or vinyl butyrate up to about 20%, it effects the quicker breaking of the dispersion emulsion of the composition upon coming into contact with the skin. Natural or synthetic rubber likewise may be added and act in the same manner. Upon rubbing, the particles then form and roll up faster into crumbs which are also larger and may be shaken off sooner and more easily. The composition is a paste or smooth cream so that it spreads well. On the other hand, the diethylene glycol mono-ethyl ether and glycol laurate and other such fatty substances tend to delay the crumb-forming action of the mixture and permit or require longer rubbing before the crumbly stage is reached and before the particles dry sufficiently to be dusted off the hands completely.

It is also possible to combine up to 100% or more of petroleum hydrocarbons (upon the weight of the fluid components of the composition) with the dry base material. When this is done, upon allowing the mixture to stand for three or four days, the composition will be found to require but little milling or none at all.

In place of the water and other liquid vehicles used, other appropriate liquids may be substituted, so long as they are compatible with the base ingredient and its characteristic properties and action in the cleaner composition as a whole.

Thus, the diethylene glycol mono-ethyl ether and diglycol laurate may be replaced by lanolin, mineral oil, sulphonated oils, or oxidized oils for raw vegetable, animal or fish oils to a degree. However, the diethylene glycol mono-ethyl ether is active as a general solvent and has beneficial action on the skin. The sorbitan mono laurate is a good wetting agent and is effective to promote uniformity of the composition and complete spreading action of the composition on the hands.

Very good results are obtained, for example, with additions of soaps such as 40 to 50 parts of alcoholic potash soap to 100 parts of the base, preferably, along with 40 to 50 parts of water or alcohol.

I claim:

1. A method of making a solid, dry, cleaner base, comprising the steps of reacting approximately 100 parts of soya bean oil with 6-12 parts of hydrated lime, cooling to 50° F., adding approximately 15 parts of sulphur monochloride diluted with one-third of its volume of inert petroleum solvent, cooling to 50° F., adding approximately 16½ parts of sulphur monochloride diluted with ½ its volume of inert petroleum solvent, with vigorous stirring until the mass solidifies as a whole.

2. A method of making a solid, dry, cleaner base, comprising the steps of reacting approximately 100 parts of soya bean oil with 6-12 parts of hydrated lime, cooling to 50° F., adding approximately 15 parts of sulphur monochloride diluted with one-third of its volume of inert petroleum solvent, cooling to 50° F., and then adding up to 10% of starch, adding approximately 16½ parts of sulphur monochloride diluted with ½ its volume of inert petroleum solvent, with vigorous stirring until the mass solidifies as a whole.

3. A method of making a solid, dry, cleaner base, comprising the steps of reacting approximately 100 parts of soya bean oil with 6-12 parts of hydrated lime, cooling to 50° F., adding ap-

proximately 15 parts of sulphur monochloride diluted with one-third of its volume of inert petroleum solvent, cooling to 50° F., adding approximately 16½ parts of sulphur monochloride diluted with ½ its volume of inert petroleum solvent, with vigorous stirring until the mass solidifies as a whole, grinding said product and dispersing the same in finely divided condition with a liquid vehicle which is non-solvent of and non-reactive upon and present in substantially equal proportions to the solid components.

4. A method of making a solid, dry, cleaner base, comprising the steps of reacting approximately 100 parts of soya bean oil with 6-12 parts of hydrated lime, cooling to 50° F., adding approximately 15 parts of sulphur monochloride diluted with one-third of its volume of inert petroleum solvent, cooling to 50° F., and then adding up to 10% of starch, adding approximately 16½ parts of sulphur monochloride diluted with ½ its volume of inert petroleum solvent, with vigorous stirring until the mass solidifies as a whole, grinding said product and dispersing the same in finely divided condition with a liquid

vehicle which is non-solvent of and non-reactive upon and present in substantially equal proportions to the solid components.

HANS BLUMBERG.
